UNITED STATES PATENT OFFICE.

JESSE EVERETT ESHBAUGH AND HERMAN C. GANTZ, OF FLINT, MICHIGAN, ASSIGNEES TO A C SPARK PLUG COMPANY, OF FLINT, MICHIGAN, A COMPANY OF MICHIGAN.

HEAT INDICATOR FOR INTERNAL-COMBUSTION ENGINES.

Application filed February 5, 1927. Serial No. 166,173.

This invention relates to improvements in heat indicators for internal combustion engines, particularly to engines used on automotive vehicles.

5 In carrying out our invention we make use of a type of indicator which changes the color of a painted surface due to the application of heat above a certain temperature. This change in color due to heat application is a well known property of certain paint substances and for convenience we position this indicator in the top opening or cap of the radiator so that it may be readily observed by the chauffeur.

15 Heat indicators placed in a similar position have been in use for some years, however, the prior devices largely making use of a thermostatic instrument such as a thermometer the bulb of which is held in the air 20 space over the water in the radiator. In our device we make use of a tube, preferably metallic, having a loop or hook at its upper portion projecting through the radiator cap or closure. This projecting portion has a 25 heat sensitive paint applied to a part of its surface or to a member attached thereto so that when the temperature within the radiator rises above a certain point the color of the painted surface will change indicating 30 to the chauffeur that the danger point has been reached.

The accompanying drawing shows three species of our device and in each modification one end of the tube is open and exposed 35 to the air space above the water of the radiator while the other end of the tube may be disposed below the surface of the water or connected to the overflow pipe.

We also, in some instances, make use of 40 a glass section in the loop end of my tube, this section being exposed to the cooling effect of the atmosphere, and as the water vapor passes through the tube it will be condensed and formed into drops which will 45 pass along the tube and back into the radiator. The flow of these drops through the glass tube will indicate to the driver that the high temperature point has been reached.

Our invention is disclosed in the accompanying drawing, in which

Fig. 1 is a transverse section through a radiator cap looking from the rear showing the application of my invention;

Fig. 2 is a view similar to Fig. 1 but of a 55 modified form, this form having a glass

shaped section projecting without the radiator cap; and

Fig. 3 is a similar view of a further modification in which one end of the heat indicator tube leads into the overflow pipe.

60 Referring to Fig. 1, 1 indicates the shell of the radiator and 2 the upper tank thereof. This tank or container has an upwardly projecting annular flange 3 to which is rigidly attached an externally threaded collar 4 65 projecting through the shell 1. Over the collar 4 there is applied the supporting part or cap 5 having openings 6 and 7 at its upper portion and these openings are provided with bushings 8 and 9 made of heat 70 resisting material.

The tube of my indicator is shown at 10, the end 11 of which is funnel shaped and projects below the surface of the water 12' in the radiator. The tube is offset at 32 and 75 at its upper end is U-shaped and has a leg 12 passing through the bushing 8 and forming a continuation of the offset 32 while the leg 13 forms a return bent portion passing through the bushing 9 and terminating at 80 14 within the air space over the water 12'. The legs 12 and 13 are connected by the horizontal portion 15 to which is applied a heat 85 sensitive paint 16 which has the property of changing its color when heat above a certain degree is applied thereto.

The ends 11 and 14 of the tube 10 are open and as the water approaches the boiling point the funnel 11 causes the water and vapor to pass upwardly by a percolating action through the tube and past the painted section 16 (which thereupon changes color), and the water is thereafter returned to the 90 radiator through the end portion 14.

The species of Fig. 2 is similar to Fig. 1 95 except that the legs 12' and 13' and the horizontal portion 15' of the U-shaped end consist of a bent tube of glass having its ends disposed within the metallic tube sections 10' and 14'. Numerals 17, 18 and 19 indicate 100 three drops of water passing through the tube.

Referring to the species of Fig. 3, it will be noted that the collar 4' is internally threaded for the reception of a threaded 105 member 5' of my heat indicator device indicated as a whole at 20. The collar 4' has an annular shoulder 21 upon which rests the disc 22 having tongues 23 fitting into recess 24 of the collar 4'. The disc 22 is loosely held 110

in position between the threaded portion 5' and the shoulder 21 and is kept from rotating by means of the tongue and groove connections 23 and 24.

5. In Fig. 3 there is also shown a top reflector portion 25 secured to the cap 5' by means of bolts 26 passing through a flange 27 on the cap 5'. The central portion 28 of the top 25 is concave and serves as a reflector for the heat sensitive paint surface 16'. As shown in Fig. 3, the paint is applied over a small screen attached to the curved part 30, although we may apply the paint directly to the tube at the part 31. Obviously the reflector may be applied to the devices shown in Figs. 1 and 2.

The tube 10' of the species of Fig. 3 has its end 11' disposed within the overflow pipe 29 and its upper end 14" return bent and opening into the air space at the top of the radiator or it may extend down into the water in the same manner as the part 10-11 of Fig. 1, in which case the circulation would be in the reverse direction from what takes place in Fig. 3. The return bent portion of the tube 10' is circular as indicated at 30 and has a section 31 which passes to the rear of the painted surface 16' and extends into a recess 33 in the lower portion of the 30 reflector 25.

The passage of the vapor through the open end 14" of the tube 10', through the loop portion 30 and into the overflow pipe 29 leading to the atmosphere will cause the heated vapor to pass the painted surface 16' and when a sufficiently high degree of temperature is reached the color of the painted surface will change.

The operation of the device shown in Figs. 40 1 and 3 is as follows: Assuming that the color of the heat sensitive paint is normally yellow, when the heated vapor passes through the tubes 10 or 10' and is sufficiently hot, it will act upon the painted surface and cause the color to change, for instance to a bright red. As the vapor cools down the color change will reverse.

We claim:

1. A heat indicating device comprising a 50 container having an opening, a closure therefor, a hollow member extending through said closure and having its end return bent and also passing through said closure, one end of said member being exposed to fluid within the container, and means for indicating tem-

perature differences in said fluid as the latter flows through said member upon change of temperature thereof.

2. The combination of claim 1, the opposite end of said member extending into the 60 medium, the temperature of which is to be indicated.

3. The combination of claim 1, the opposite end of said member being of funnel 65 shape and extending below the surface of a liquid the temperature of which is to be indicated.

4. The combination of claim 1, said means comprising a heat sensitive paint applied to that portion of the member extending 70 through said closure.

5. The combination of claim 1, said return 75 bent portion being of inverted U-shape, and a coating of heat sensitive paint applied to the base of the U.

6. Means for indicating the condition of liquid in a container comprising a tube extending down into said liquid from above the level thereof and adapted to allow the fluid to pass therethrough, said tube having a 80 funnel shaped opening, means associated with said tube for giving a visible indication when fluid passes through said tube, and means for returning said fluid to said container.

7. A heat indicating device comprising a supporting part, a heat transmitting member extending through said part and having its end return bent and passing through said part, one end of said member being exposed 90 to the temperature differences of the body whose thermal condition is to be indicated, and means at the return bent portion for indicating said differences.

8. In a heat indicating device, a container 95 having a closure, a hollow tube extending through said closure at a plurality of openings therein, bushings in said openings surrounding said tube, and means on said tube for indicating temperature differences. 100

9. In a heat indicator, a container having a closure, a U-shaped tube passing through said closure the legs of said U being of unequal length, and means on said tube for indicating temperature differences of the 105 body to which the indicator is applied.

In testimony whereof we affix our signatures.

JESSE E. ESHBAUGH.
